(57) CLAIM

The ornamental design for a hair extension, as shown and described.

DESCRIPTION

FIG. 1 is a rear perspective view of a hair extension, showing a first embodiment of my new design shown in a condition of use on a person;

FIG. 2 is a rear perspective view of FIG. 1, the person being omitted;

FIG. 3 is a front perspective view of FIG. 2;

FIG. 4 is a top plan view thereof, illustrated in a straight position;

FIG. 5 is a bottom plan view of FIG. 4;

FIG. 6 is a left-side elevational view of FIG. 4, the right-side elevational view, front elevational view, and rear elevational view all being identical thereto.

FIG. 7 is a rear perspective view of a second embodiment thereof, shown in the condition of use on the person;

FIG. 8 is a rear perspective view of FIG. 7, the person being omitted;

FIG. 9 is a front perspective view of FIG. 8;

FIG. 10 is a top plan view thereof;

FIG. 11 is a bottom plan view of FIG. 10; and,

FIG. 12 is a left-side elevational view of FIG. 10, the right-side elevational view, front elevational view, and rear elevational view all being identical thereto.

The broken lines in the drawing depicting the person with hair and the double hair band are for illustrative purposes only and form no part of the claimed design.
